PAD HOLDER

Vernon B. Trevelyan, Chicago, Ill., assignor to
Cleanser Products, Inc., Chicago, Ill., a corpo-
ration of Illinois

Application July 13, 1936, Serial No. 90,352

1 Claim. (Cl. 15—143)

My invention relates to holders for pads to be used in scouring, polishing or cleaning metal, wood or textiles. It is designed particularly to protect the fingers of the operator from contact 5 with steel wool, liquids or powders used in polishing or cleaning, and to catch drippings from the pad after it has been used, and the holder is to act as a self stand to be set down at any convenient place.

10 In the accompanying drawing—

Fig. 1 is a perspective view of the holder;

Fig. 2 is a sectional elevation of the holder and a pad contained therein, the same being used in a scouring or polishing operation; and

15 Fig. 3 is an elevation of a holder and pad, the holder being partly broken away to show the sump for catching drip from the pad when the device is not in use.

The holder is of spring metal, and is formed 20 by stamping a blank from sheet steel or other suitable material. The blank is bent to form two arms 11 and 12 of unequal dimensions, which arms are connected together by an intermediate part 13 which serves as a base on which the device stands when not in use.

25 The two arms are substantially parallel with each other and at right angles to the base. The outer face of each arm is pressed inward to form an exterior recess, with a consequent inward bulge 30 on the inner face toward a corresponding inward bulge on the opposite arm. On arm 11, the recess is adapted to receive the thumb of the operator, as shown in Fig. 2. On arm 12, the recess is wide enough to receive the first, second and third fingers of the operator. At the tips of the arms, beyond the recesses, the metal turns outward as 35 shown at 14 and 15. The purpose of this construction is to protect the digits of the operator

from contact with material used in the pad, when scouring pots and pans.

At the end of the base 13, and integral with the arms, are lips 16 which form a pocket or sump to catch drip from the pad after it has been used, 5 and while the device is standing in the position shown in Fig. 3.

On the arm 12, and at an elevation about equal to the height of the top of arm 11, are two small prongs 17 which extend toward the opposite arm. 10 They are conveniently punched from the metal of arm 12. They serve as prick points to prevent the pad from slipping in the holder while it is being used, while at the same time not interfering with inserting or adjusting the pad in the 15 holder.

In this connection, it may be observed that, when inserting the pad in the holder, the upper edges of arm 12 are conveniently grasped between thumb and fingers of one hand while the other hand presses an edge of the pad against the inward bulge on arm 11, and adjacent to its tip 14. 20

This action opens the spring arms and permits the easy insertion of the pad between said arms. When the device is being used, as shown in Fig. 2, 25 25 the grasping action of thumb and fingers presses the arms toward each other and holds the pad firmly.

What I claim is:

A pad holder formed of spring metal and having two substantially parallel arms between which a pad may be held by the initial spring action of the arms, the metal between the arms forming a base integral with the arms and upon which the holder may stand when not in use, and also providing a sump for catching drip from a pad held between the arms of the holder. 30 35

VERNON B. TREVELLYAN.
